ALFRED MOLE, Inventor
by *Charles D. Daniels* Atty.

UNITED STATES PATENT OFFICE.

ALFRED MOLE, OF FORDSBURG, TRANSVAAL.

DEVICE FOR BALANCING SASHES.

No. 878,983.

Specification of Letters Patent.

Patented Feb. 11, 1908.

Application filed July 24, 1906. Serial No. 327,474.

To all whom it may concern:

Be it known that I, ALFRED MOLE, a subject of the King of Great Britain, and resident of Fordsburg, Transvaal, have invented 5 certain new and useful Improvements in Devices for Balancing Sashes, of which the following is a specification.

This invention relates to the hanging of window sashes and more particularly to 10 sashes hung so that they balance each other.

The primary object of the present invention is to provide for the hanging of the sashes without the employment of weights, weight boxes and the usual fittings while at 15 the same time permitting the top sash to be opened without opening the bottom sash and so that the top sash will travel at twice the speed of the bottom sash.

According to the present invention the 20 sashes are connected with each other at each side by means of a rope chain or cord. One end of each of the cords is fixed in a convenient manner to the pulley stile at or about the level of the top rail of the bottom sash. 25 The cord, rope or chain, from its point of attachment to the pulley stile passes down a recess or groove therein, under a pulley which is fixed to the side rail of the bottom sash and is movable with it, then up and round a pulley arranged above the head or in the top of 30 the window frame, then in a downward direction and down a groove in the side rail of the top sash to which it is preferably adjustably fixed.

The invention will now be described in detail by aid of the accompanying drawings, 35 wherein

Figure 1 represents an elevation of a window frame, from the inside, showing the top 40 and bottom sashes open, and Fig. 2 is a section of Fig. 1 on line x—x.

A represents the top sash comprising the top rail a, the bottom rail a¹ and the two side rails a² a³. B is the bottom sash of which b 45 is the top rail, b¹ the bottom rail and b² b³ the side rails.

The bottom rail a¹ of the top sash and the top rail b of the bottom sash constitute the meeting rails when the window is closed. In 50 the drawing the bottom sash B is shown twice the height or length of the top sash A so that the weight of the bottom sash is approximately twice that of the top sash. The window frame comprises the sill C, the outside 55 and inside linings c c¹, the pulley stiles c² c³,

the parting bead c⁴, the head c⁵, and the head inside and outside linings c⁶ c⁷.

On the head c⁵ at each side of the window frame is fixed a bracket or casing D in which is revolvably mounted a grooved pulley d. 60 These pulleys d are set so that their axes are over the center of the parting beads c⁴ and the diameter of the pulleys is equal or approximately equal to the distance between the centers of the sashes A B. In the case of 65 thick sashes instead of increasing the diameter of the pulley d, two pulleys at each side of the frame might be employed. These pulleys d are preferably first fixed to a piece of wood E which may be fixed to the head c⁵ by 70 screws screwed in from the underside. To provide for access to the pulleys d a pocket may be provided at the center of the head so that by unscrewing the screws either pulley d may be removed and replaced. The pocket 75 may be provided either in the process of manufacture or may be cut therein after the window has been fixed, should it be necessary at any time to obtain access to the pulleys.

Two chains, ropes or cords e are employed, 80 one for each side of the window. I prefer to employ wire ropes e of a suitable thickness as they are not so liable to stretch after being fixed and adjusted. One end of each of the ropes e is fixed to the pulley stile c² c³ at or 85 about the level of the top rail b of the bottom sash when the latter is in its closed position. This end of the wire e may be fixed either by nails or screws, or, but preferably, by turning it round a small pin and splicing it into 90 itself.

e¹ represents the fixing attaching the end of the rope to the pulley stile c² c³. The pulley stile is constructed with a vertical groove or recess e² down which the rope e passes from its point of attachment to the stile. To the side rail b² b³ of the bottom sash is fixed a pulley F which runs in grooves f formed in the side rail of the bottom sash B and the recess or groove e² in the pulley stile. The 95 rope e passes under this pulley F, then up a vertical groove f formed in the side rail of the bottom sash B on the inside and over the pulley d fixed to the head c⁵. The cord e then 100 passes in a downward direction down a groove f¹ in the inner edge of the side rail of the top sash A, being attached at its lower extremity to a loop or U shaped piece of wire H fixed to a nut h located in a recess f² in the side rail 105 of the top sash A. A hole f³ is formed in the 110

bottom rail a^1 of the top sash passing up into the recess f^2 . In the hole f^3 and projecting up into the recess f^2 and engaging the nut h is a screw or bolt h^1 the head h^2 of which is located in a recess f^4 in the bottom edge of the bottom rail a^1 . The arrangement is the same at each side of the window.

- The construction and operation of the means for adjusting the ropes are the same as 10 those described in my prior application previously referred to. By turning the screw or bolt h^1 in one direction the cord e may be lengthened and by screwing it in the reverse direction the nut h and loop H are drawn 15 down, drawing down the rope e to take up any slack.

It will be understood that the weight of the bottom sash B being twice the weight of the top sash A, and half the weight of the bottom 20 sash being carried by the ends of the cords e fixed to the pulley stile c^2 c^3 , the other half which is carried by the ends of the cords e fixed to the top sash A, serves to balance the latter. Instead of making the bottom sash 25 twice the size of the top sash, it will be evident that the same result may be attained should the sashes be made of the same dimensions, to make the bottom sash twice or approximately twice the weight of the top sash by 30 constructing it of heavier wood and glazing it with heavier glass.

To enable the top sash A to be opened without opening the bottom sash B or without leaving any through passage under the lower 35 edge of the bottom sash, the window frame should be constructed with a deep sill as indicated at C. If this sill C be made say three inches deep then the bottom sash B may be raised three inches without opening it to the 40 outside, while the top sash A will be lowered six inches or thereabouts. Assuming the

bottom sash B to have been raised so that an opening of say four inches is left between the bottom rail b^1 and the top of the sill C, then the bottom sash B will have been raised a 45 total distance of seven inches and the opening between the top rail a of the top sash A and the head c^5 of the window frame will be fourteen inches or thereabout.

A small pocket indicated at J is cut in the 50 pulley stile c^2 c^3 at one side of the window frame up to the groove or recess e^2 in which one half of the pulley F runs, to permit the pulley to pass in and out of said groove or recess in the operation of removing the sash B 55 from the window frame. A corresponding pocket indicated at J^1 may also be provided in the inside lining c so as to allow of access to the pocket J in the pulley stile without disturbing the lining after the window has been 60 fixed. The inside lining may have two saw-cuts made in it to locate the position of the pocket J in the pulley stile so that the piece could be cut out should it at any time be required to remove the sash.

What I claim as my invention and desire to protect by Letters Patent is:—

In combination, upper and lower sashes, pulleys fixed to the lower sashes, pulleys fixed to the window frame, cords each fixed 70 at one end to the window frame, passing around said pulleys, and each fixed to the upper sash, and means carried by the upper sash for adjusting each of said cords.

In witness whereof I have hereunto set my 75 hand in the presence of two subscribing witnesses.

ALFRED MOLE.
